UNITED STATES PATENT OFFICE.

SARAH A. PEARSALL, OF ROCKVILLE CENTER, NEW YORK.

VEIL-CLASP.

1,223,608.

Specification of Letters Patent. Patented Apr. 24, 1917.

Application filed May 24, 1916. Serial No. 99,626.

To all whom it may concern:

Be it known that I, SARAH A. PEARSALL, a citizen of the United States, residing at Rockville Center, in the county of Nassau 5 and State of New York, have invented certain new and useful Improvements in Veil-Clasps; and I do hereby declare the following to be a full, clear, and exact description of the invention, such as will enable others 10 skilled in the art to which it appertains to make and use the same, reference being had to the accompanying drawings, and to the letters and figures of reference marked thereon, which form a part of this specification. 15

This invention relates to new and useful improvements in veil clasps and consists of a simple and efficient device of this nature so arranged that the folds of a veil may be 20 clasped and securely held.

The invention comprises various details of construction, combinations and arrangements of parts, all as will be more fully hereinafter described, shown in the accompanying drawings and then specifically defined in the appended claims.

My invention is illustrated in the accompanying drawings, in which:—

Figure 1 is a top plan view of my improved veil clasp.

Fig. 2 is a bottom plan view.

Fig. 3 is an end view.

Fig. 4 is a view showing the clasp open.

Fig. 5 is a sectional view on line 5—5 of Fig. 1.

Reference now being had to the details of the drawings by letter, A, A designate the wings of a butterfly clasp, the inner edges of which are turned to form cylindrical rolls 40 A' and B', each provided with an angled slot, slots C and D and a sleeve E shown in Fig. 5 of the drawings, is provided with shoulders F between which the two rolls of the wings are journaled. Said sleeve is provided with elongated slots H in alignment with each other, and K is a push rod mounted within the sleeve and bearing against the inner end of the spring N, which latter is inserted in the inner end of the sleeve and bears against the end wall thereof. The purpose of said spring is normally to hold the rod K in the position shown in Fig. 5 50 of the drawings.

Pins O and P project from the rod K and 55 extend through the slots in the sleeve, the pin O passing through the angled slot C,

while the pin P passes through the angled slot D, the purpose of said pins engaging the slots in the manner shown in Fig. 1 being to lock the wings open or in the position shown in Fig. 2 of the drawings. A spring, designated by letter R, has slits S in its ends, portions intermediate the slits and the marginal edges being bent in opposite directions, said springs being for the purpose of opening the wings after being released. The ends of the springs engage the slotted straps T formed by the under surface of the wings at any suitable locations upon the pivotal portions thereof and the spring bears against the inner marginal portions of the rolls of the wings. Curved spurs, designated by letter T', project from the rolled portions of the wings and are positioned substantially opposite each other 75 and are designed to grip the veil or other object upon which the clasp is held.

Said spring normally serves the purpose of throwing the wings to the position shown in Fig. 3 of the drawings, and the slotted straps T serve as reinforcing means to brace the wings.

In operation, when the device is to be applied to the folds of a veil or other object, the wings are pushed down to the position 85 shown in Fig. 2 of the drawings and, when they approach such position, the two pins O and P upon the push rod will come in alignment with the longitudinal portions of the angled slots and the coiled spring N will 90 tend to throw the pins to the position shown in Fig. 1 and which will lock the wings in position shown in Fig. 2, the spurs gripping the veil or other object to which the device is to be applied. To release the veil clasp, 95 the operator merely pushes in upon the end of the rod K, sufficient to bring the pins opposite the lateral projections of the angled slots, after which the spring R will throw the wings to the position shown in Fig. 3, 100 thus releasing the spurs from the object engaged thereby.

What I claim to be new is:—

1. A veil clasp comprising two wings having portions turned into rolls which are 105 provided with angled slots, a sleeve upon which the wings are journaled, said sleeve being slotted, a spring-pressed push rod movable within the sleeve and having pins projecting from the slots in the wall of the 110 sleeve and angled slots in said rolls, and spurs upon the wings for gripping the veil.

2. A veil clasp comprising two wings, the inner marginal edges of which are turned into cylindrical rolls which are provided with reversely-arranged angled slots, a sleeve upon which said rolls are journaled, shoulders upon the sleeve preventing longitudinal movements to the wings, a spring-pressed push rod mounted in the sleeve, pins projecting from said rod and movable within the slots of the sleeve and rolls of the wings, oppositely disposed spurs projecting from said rolls and designed to grip a veil, and springs bearing against the wings.

3. A veil clasp comprising two wings, the inner marginal edges of which are turned into cylindrical rolls which are provided with reversely-arranged angled slots, a sleeve upon which said rolls are journaled, shoulders upon the sleeve preventing longitudinal movements to the wings, a spring-pressed push rod mounted in the sleeve, pins projecting from said rod and movable within the slots of the sleeve and rolls of the wings, oppositely disposed spurs projecting from said rolls and designed to grip a veil, and springs bearing against the wings.

tudinal movements to the wings, a spring-pressed push rod mounted in the sleeve, pins projecting from said rod and movable within the slots of the sleeve and rolls of the wings, oppositely disposed spurs projecting from said rolls adapted to grip a veil, slotted bars, one upon each wing, a flat spring having slotted ends passing through the slots of said bars, said springs curved in opposite directions upon their inner ends, said springs serving to normally throw the wings to their limits in one direction.

In testimony whereof I hereunto affix my signature in presence of two witnesses.

SARAH A. PEARSALL.

Witnesses:

JOSEPH N. PEARSALL,
A. L. HOUGH.
